UNITED STATES PATENT OFFICE

155,884

DESIGN FOR A COIN CHANGER

James Scott Gassaway, West Los Angeles, Calif.

Application January 24, 1949, Serial No. 437

Term of patent 14 years

(Cl. D52—4)

To all whom it may concern:

Be it known that I, James Scott Gassaway, a citizen of the United States of America, resident of West Los Angeles, in the county of Los Angeles, State of California, have invented a new, original, and ornamental Design for a Coin Changer, of which the following is a specification, reference being had to the accompanying drawing forming a part thereof:

In the drawing,

Fig. 1 is a perspective view of a coin changer, showing my new design;

Fig. 2 is a back view of the coin changer; and Fig. 3 is a side view of the coin changer.

I claim:

The ornamental design for a coin changer, as shown.

JAMES SCOTT GASSAWAY.
